UNITED STATES PATENT OFFICE

112,068

DESIGN FOR AN ELECTRIC LIGHTING FIXTURE

Dean H. Holden, Cleveland, Ohio

Application March 2, 1938, Serial No. 75,537

Term of patent 7 years

To all whom it may concern:

Be it known that I, Dean H. Holden, a citizen of the United States and a resident of Cleveland, county of Cuyahoga and State of Ohio, have invented a new, original, and ornamental Design for an Electric Lighting Fixture, of which the following is a specification, reference being had to the accompanying drawing, forming a part thereof.

In said annexed drawing:

Fig. 1 is a plan view of the electric lighting

fixture embodying my new design; Fig. 2 is a side view of the fixture shown in Fig. 1; and Fig. 3 is an end view of such fixture.

The dominant feature of my design resides in the upper and lower support members in combination with the lighting fixture shown.

I claim:

The ornamental design for an electric lighting fixture, as shown and described.

DEAN H. HOLDEN.
